UNITED STATES PATENT OFFICE

BRYAN GROOM, OF GALASHIELS, SCOTLAND

RADIO LOUD-SPEAKER

Application filed April 29, 1929, Serial No. 358,805, and in Great Britain May 14, 1928.

This invention relates to radio loud speakers of the kind including a diaphragm and a non-resonant baffle which is so located relatively to the diaphragm that it serves to restrict the passage of air from one side of the diaphragm to the other.

In connection with loud speakers of this type it is usual so to mount the baffle that it surrounds the diaphragm. The effect of so mounting the baffle is to strengthen the bass notes and it is found that excessively strong bass notes are objectionable to certain listeners.

An object of the invention is to provide a loud speaker incorporating means for varying the strength of the bass notes relatively to that of the treble notes.

The invention provides a loud speaker in which the diaphragm and the baffle are telescopically related and in which the end of the baffle nearest the diaphragm is located within the diaphragm or within an extension thereof.

Three embodiments of the invention are illustrated diagrammatically in the drawing in which Fig. 1 is a section of a loud speaker incorporating a conical diaphragm and a conical baffle provided with cylindrical extensions, Fig. 2 a section of a loud speaker incorporating a flat diaphragm having a cylindrical extension accommodating a cylindrical extension of a conical baffle and Fig. 3 a section of a loud speaker incorporating two nested cones.

The loud speaker shown includes a diaphragm 1 carrying a coil drive 2. A usual pot magnet is denoted at 3, the field winding of which is indicated conventionally at 4 (Figs. 1 and 2). A non-resonant baffle denoted at 5 is as usual so located relatively to the diaphragm 1 that it serves to restrict the passage of air from one side of the diaphragm to the other. In the three embodiments illustrated the diaphragm 1 and the baffle 5 are telescopically related and the end of each baffle nearest the corresponding diaphragm 1 is located either within the diaphragm 1 or within an extension thereof.

According to the embodiment illustrated in Fig. 1 there is employed a conical dia-

phragm 1 having a cylindrical tubular extension 6 and a conical non-resonant baffle 5 having a cylindrical tubular extension 7, the extension 7 being located within and in close proximity to the extension 6.

In the embodiment illustrated in Fig. 2 a flat diaphragm 1 is provided with a cylindrical extension 6 and a conical baffle 5 having a cylindrical extension 7 which is located within and in close proximity to the extension 6.

According to the embodiment illustrated in Fig. 3 the diaphragm 1 and the baffle 5 comprise two nested cones, the cone constituting the baffle 5 being located within the cone constituting the diaphragm 1.

It will be seen that, in the forms shown in Figs. 1 and 2 the diaphragm extension overlaps the baffle extension and that the efficiency of the seal will depend on the extent of the overlap.

I claim:—

1. A radio loud speaker of the class described comprising, in combination, a diaphragm and a non-resonant baffle arranged in telescopic relationship with said baffle and with the end nearest said diaphragm within said diaphragm.

2. A radio loud speaker of the class described comprising, in combination, a diaphragm having a tubular extension and a non-resonant baffle having a second extension arranged in telescopic relationship with and located within said first extension.

3. A radio loud speaker of the class described comprising, in combination, a diaphragm having a cylindrical tubular extension and a non-resonant baffle having a second extension arranged in telescopic relationship with and located within said first extension.

In testimony whereof I have signed my name to this specification.

BRYAN GROOM.
